CLAIM

The ornamental design for a sterilizer as shown.

DESCRIPTION

FIG. 1 is a perspective view showing a sterilizer design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the sterilizer shown in broken lines are included for the purpose of illustrating unclaimed portions of the sterilizer and form no part of the claimed design.

1 Claim, 6 Drawing Sheets
